CLAIM

We claim the ornamental design for a data capture device, as
shown and described.

DESCRIPTION

FIG. 1 is a rear perspective view of a data capture device;
FIG. 2 is a bottom perspective view thereof;
FIG. 3 is a front perspective view thereof;
FIG. 4 is a first side view thereof;
FIG. 5 is a second side view thereof;
FIG. 6 is a top view thereof;
FIG. 7 is a bottom view thereof;
FIG. 8 is a front view thereof; and,
FIG. 9 is a rear view thereof.
Broken lines and unshaded portions contained within broken
lines depict portions of the data capture device that form no
part of the claimed design but are shown for illustrative
purposes.
